Inventor:
Arthur W. Buck,
By Hugh K. Magnet,
Atty.

UNITED STATES PATENT OFFICE.

ARTHUR W. BUCK, OF ST. LOUIS, MISSOURI.

DENTAL FILM PACK OR PACKET.

Application filed January 14, 1921. Serial No. 437,345.

To all whom it may concern:

Be it known that I, ARTHUR W. BUCK, a citizen of the United States, residing at the city of St. Louis, in the State of Missouri, have invented certain new and useful Improvements in a Dental Film Pack or Packet, of which the following is a specification.

This invention provides means for the patient's holding a dental X-ray film while the operator is making a Röntgenograph, which means serves, also, as means to prevent a child or a nervous patient from swallowing the packet containing the film.

In making X-ray pictures of the teeth, it has been found from practical experience that the smaller the dental-film packet used the greater the convenience to the doctor and the patient, providing that the packet is sufficiently large to permit the X-raying of one tooth. Such a small packet might, however, be swallowed by a nervous patient or a child, the result of which would probably prove a serious detriment. It has been found, also, that, in a great many instances, patients are more or less nervous and that there is considerable difficulty in getting a dental-film packet held in the correct position. It is the universal custom for the patient to hold the packet in position with his or her own finger, and as the packets heretofore used possess no guide of any kind, the patient frequently allows the packet to slip out of position, which fact is not discovered until the film is developed.

In the accompanying drawings forming part of this specification, in which like numbers of reference denote like parts wherever they occur.

Figure 1 is a front elevation of a commercial dental film pack embodying the invention;

Figure 2 is a side elevation of the film pack, and Figures 3 and 4 are, respectively, front and side elevations of a modification of the invention.

Referring to the drawing, this invention consists of a dental-film packet 1 of small size, and for the purposes of the present invention preferably of a rectangular or oblong formation, having its opposite corners rounded off in a manner to not in any way injure the mouth or gums of the user when inserted into operative position, and to one side or one end of which is attached or

formed a right-angled projection 2, which projection, when formed separately thereof, may be made of cork, rubber, wood, or any other suitable material, and, in any case, is designed to be yieldable or compressible under the gripping action of the teeth of a patient, whereby any tendency for accidental displacement of the film packet from correct position is reduced to a minimum. The projection may be molded integral with the packet or attached thereto by an adhesive or the like. This projection will rest on the crown of the tooth and act as a guide to enable the patient to hold the same in the proper position, and it, also, increases the size and thickness of the packet in such a manner as to overcome the probability of the patient's swallowing the packet, which is of special importance in X-raying teeth.

The projection 2 is preferably provided with rounded corners 3 and 4, and may extend clear across the packet to which it is attached or only part way, but the principal feature of this invention is a dental-film packet possessing a permanent projection extending at approximately a right angle to the packet.

In the drawing, the projection 2 is shown as being preferably coextensive with one of the marginal edges of the packet 1, and its opposite ends rounded off to conform to the rounded corners of the latter complementary thereto, whereby to further prevent injury to the mouth or gums of the user.

Likewise, the projection 2 is shown flush with the margin of the packet 1, but may, if desired, be merely adjacent thereto.

In its preferred embodiment as shown, the device is in the form of a commercial dental film pack 1, of the rectangular or oblong shape as hereinbefore mentioned, with the extension 2, preferably in the form of a bead or rib, attached thereto by adhesive or other means to form a unitary article of manufacture and extended across the upper or outer face of the film pack 1 at or near one of the marginal edges thereof, whereby, when the extension 2 is engaged on or otherwise gripped between the teeth of a person, the film pack 1 will have its front face disposed directly in rear of either one or more, depending upon its area or size, of the teeth of the upper or lower sets of the same, and will remain in such position

as long as the person maintains a bite on the extension.

In Figures 1 and 2 the projection 2 has been shown as engaged with one end of the 5 packet. However, if desired, this projection may be arranged to lie parallel with the lateral margins of the packet as shown in Figs. 3 and 4 of the drawings.

Having thus described this invention, I 10 hereby reserve the benefit of all changes in form, arrangement, order, or use of parts, as it is evident that many minor changes may be made therein without departing from the spirit of this invention or the scope of the 15 following claims.

I claim:

1. A new article of manufacture consisting of a photographic film pack provided at one extreme edge with a laterally projecting flange. 20

2. A new article of manufacture consisting of a photographic film pack provided at one extreme edge with a laterally projecting flange, the flange extending the entire length of said edge and the corners of the pack 25 and ends of the flange being correspondingly rounded.

In testimony whereof I hereunto affix my signature.

ARTHUR W. BUCK.
